US00D943003S

(12) **United States Design Patent** (10) **Patent No.:** **US D943,003 S**
Boyce (45) **Date of Patent:** **** Feb. 8, 2022**

(54) **ROTARY ATOMIZER**

- (71) Applicant: **HOTSTART, Inc.**, Spokane, WA (US)
(72) Inventor: **Benjamin J. Boyce**, Spokane, WA (US)
(73) Assignee: **HotStart, Inc.**, Spokane, WA (US)
(**) Term: **15 Years**
(21) Appl. No.: **29/766,134**
(22) Filed: **Jan. 13, 2021**

Related U.S. Application Data

Primary Examiner — Rebecca Tsehay(74) *Attorney, Agent, or Firm* — Lee & Hayes, P.C.(57) **CLAIM**

The ornamental design for a rotary atomizer, as shown and described.

DESCRIPTION

FIG. 1 is a front perspective view of a rotary atomizer;
FIG. 2 is a front view thereof;

FIG. 3 is a back view thereof;
FIG. 4 is a left-side view thereof;
FIG. 5 is a right-side view thereof;
FIG. 6 is a top view thereof; and,

FIG. 7 is a bottom view thereof.
The dashed broken lines depict portions of the rotary atomizer that form no part of the claimed design.
